UNITED STATES PATENT OFFICE.

GEORGE BENZE AND WILLIAM BENZE, OF NEW YORK, N. Y.

DESIGN FOR A RECEPTACLE FOR COINS.

SPECIFICATION forming part of Design No. 24,694, dated September 24, 1895.

Application filed July 25, 1895. Serial No. 557,129. Term of patent 3½ years.

To all whom it may concern:

Be it known that we, GEORGE BENZE and WILLIAM BENZE, of New York, in the county and State of New York, have invented and produced a new and original Design for a Receptacle for Coins and other Articles, of which the following is a full, clear, and exact description.

This design relates to a receptacle for coins, pins, fasteners, &c.

Reference is to be had to the accompanying drawing, forming a part of this specification, the figure being a perspective view of a receptacle embodying our new design.

The design consists in the base figure 1, in the center of which appears the circular figure 2, giving the same a concave disk-like

appearance, and at its center is displayed the representation of a coin, medallion, or the like.

The leading feature of the design resides in the base, showing a concave figure 2, displayed with a medallion-like figure at its center.

We claim—

The design for a receptacle for coins and other articles, substantially as shown and described.

GEORGE BENZE.
WILLIAM BENZE.
